UNITED STATES PATENT OFFICE.

LEON H. BEYTES, OF NORTH PLYMOUTH, MASSACHUSETTS.

CONTROL MECHANISM FOR HEAD AND BOX MOTIONS OF LOOMS.

Application filed July 19, 1927. Serial No. 206,900.

My invention relates to looms and more specifically aims to provide an improved pattern or operating sequence control mechanism for the head-motions and box-motions of 5 looms.

In the accompanying drawings illustrating by way of example certain embodiments of my invention.

Fig. 1 is a view in vertical section, somewhat diagrammatic, of a portion of a loom head-motion having mechanism in accordance with one form of my invention applied to it;

Fig. 2 is a view in end elevation and upon a larger scale of a section of pattern chain and its actuating element or pattern cylinder similar to that shown in Fig. 1;

Fig. 3 is a broken view partly in elevation and partly in section through a portion of 20 the mechanism of Fig. 2, but one bar of the chain being shown, for the sake of clearness;

Fig. 4 is a view similar to Fig. 2 illustrating a plurality of separate pattern chains on the same cylinder capable of receiving a 25 single wider chain;

Fig. 5 is a transverse section through a cylinder having a plurality of chains of different lengths thereon; and

Fig. 6 shows a fastener, upon a larger scale.

Referring more particularly to the drawings and first to Fig. 1, the loom parts shown in illustration of one adaptation of my invention include a vibrator lever 1, a series of which is provided, these being the movable parts to be acted upon by the pattern mechanism. Each vibrator lever 1 carries a vibrator gear 2, adapted to mesh with one or the other of the cylinder gears 3, 3 accordingly as its vibrator lever is raised or lowered 40 as controlled by the pattern mechanism. Engagement of a vibrator gear with one or the other of said cylinder gears will cause the corresponding harness jack 4 to be moved in one or the opposite direction through the connector 5, thereby raising or lowering the harness connected to that particular jack.

Looking now more particularly at Figs. 2 and 3 the pattern controlling device there shown as illustrating my invention comprises a series of transverse bars or carrier bars, pins or the like 7, each adapted to receive a row of pattern elements including the sinkers or plain members 8 and the risers or cam members 9. The sinkers 8 constituting 55 one form of means for holding or locating the

risers in the selected positions along a bar as shown are in the form of collars or bushings and may have a length of one, two, three or more units as the pattern arrangement may require, or the desired number of single or other unit sinkers may be used in line upon a bar.

Each riser 9 comprises a centrally apertured hub portion 10 and a body or cam portion 11 of disk-like form which may be termed the riser disk. Said hub portion projects laterally and axially at both faces of the riser disk, as illustrated, to a sufficient distance to cooperate with bearing means for externally supporting the riser at its hub positively and accurately, as will later be more fully described. The full width of the riser axially thereof, including both the disk or cam and the hub portion is substantially equal to that of a sinker of single unit length. As 75 stated, the riser disk is positioned in the manner of a flange substantially centrally between the ends of the hub so that a double, external hub bearing is always provided for each riser, one such hub bearing at each face 80 of each riser disk.

Successive bars 7 carrying the variously arranged risers and sinkers are connected in parallelism as by the links 12 at the opposite ends of the bars. Said links, in their preferred form and as best seen in Fig. 5, are of arcuate shape having a bearing or eye 13 at each end for receiving the respective bars, I preferably and in actual practice provide links of markedly increased thickness 90 over that heretofore customary, at least at their eyes, for example equal to about half the axial extent of a sinker or of a riser, as illustrated, so that two links together will occupy on a bar substantially the space of one sinker or one riser, or each link eye or entire link may correspond to a full沉sinker or riser, or may be otherwise proportioned. The links thus have an extended bearing engagement 95 with their bars, so that the latter are accurately held in parallelism, with little or no play. Due to this extensive bearing surface between the bars and the links the latter do not tend to shear the bars or wear them excessively in the manner of the thin sheet-metal 105 and blade-like links commonly employed.

The links 12 may be held in place upon the bars by any suitable means but I have herein shown for this purpose an improved fastening device. The bars or pins 7 are formed 110

with annular grooves 14 near their ends, at the outer faces of the links, for the reception of the fasteners 15; see Fig. 6. These latter may be resilient washer-like devices adapted to be sprung about the bars and into said grooves 14, or pliable wire-like broken rings pressed into the grooves, one form of which is illustrated in Fig. 6, or other means substantially encircling the bar axis and seating in said grooves. Said fastening means is a distinct improvement upon the former cotter pin type, since it provides bearing engagement with the adjacent face of a link substantially completely around the bar, and acts additionally to hold the links in alignment and the bars in parallelism, thus making for better cooperation of the chain with its actuating element or cylinder and for smoother and quieter operation in general.

In the form of fastener 15 shown upon a larger scale in Fig. 6 I obtain a maximum radial thickness of stock and necessary resiliency in a fastener of least overall diameter, the wire-like blank, preferably substantially square in cross-section, of which it is formed having its ends bent back upon themselves internally of the fastener, with a definite gap left between the extreme ends of the inturned parts, so that only the outer ring of material would be sprung in applying or removing the fastener, which is preferably of a size to lie within the contour of an adjacent link.

The cotter fastening referred to must be bent or spread and if very short cotters are used they are apt to be forced out, while if sufficiently long cotters are used the bent or spread ends frequently catch in other parts of the chain or in the various devices that are used in carrying long chains, whatever the type of chain carriers, with resulting defective operation, loom stoppage or breakage of parts.

My pattern chain thus comprises a series of bars carrying risers located in selected position therealong as by the sinkers herein illustrated for the purpose by way of example, said bars being connected for pivotal movement in parallelism with each other by the links and fasteners. The corresponding risers and sinkers on successive bars are disposed in alignment, each line of risers and sinkers in the direction of the length of the pattern chain comprising what may be termed one control path or control line. In the connection herein illustrated, each such control line determines the operation of one loom harness, or the combination of two control lines may determine the positioning of one cell of a shuttle box as in the case of the chain shown at the left in Fig. 2.

A pattern chain as shown and described may be employed in connection with a driving element or "pattern cylinder" of the usual form, which comprises merely a shaft having sprockets at its opposite ends for

engagement with the ends of the chain bars. Owing to the improved links and fastening devices, with resultant decrease in play and wear of the parts, superior operating results are obtained. Also due to the relatively narrow cam surface of the risers, as compared with the whole width of one control path, all chance of one riser actuating two vibrator levers simultaneously, with resulting "harness skip," is avoided. But if said usual "pattern cylinder" with widely separated sprockets is used, the bars and the sinker and riser members thereon are without support or guidance intermediate the chain sides. Also in such case one longitudinal line of collars similar to sinkers must be provided at each side of the chain at the inner faces of the links for engagement with the two sprockets. The chain of my invention, however, is particularly advantageous in combination with an improved driving element or "pattern cylinder" whereby said disadvantages are overcome and the full space between the links may be used for risers and sinkers.

Referring again to Figs. 2 and 3, said novel driving element comprises a central core or shaft 16 having its ends formed for reception in suitable bearings. Disposed along and coaxial with the shaft is a series of plates, ring formations, or rings 17 spaced, preferably equally, and constructed to provide annular, inter-ring, riser-disk receiving or guiding paths or grooves 18. Each such ring, which may be formed integrally with the shaft or as a separate piece fitted and secured to it, has in its edge a plurality of transverse notches or arcuate recesses 19 equally spaced about the ring, any suitable number being provided according to the dimension of the shaft and of the links, risers, etc. In the present case I have illustrated six notches to each ring. Adjacent rings 17 are arranged with their respective notches in alignment longitudinally of the shaft, at least throughout any such successive plurality of rings as will cooperate with one pattern chain. If desired the said rings may be angularly adjustable upon the shaft where a plurality of chains are to be employed so that one chain may be advanced relatively to another.

The respective aligned series of notches 19 in a number of rings 17 thus constitute in effect a plurality of equally angularly spaced grooves each adapted to receive and afford external bearing support for the hubs of all risers of a given row or bar, each riser being directly supported at both sides of its disk, by reason of the central location of the latter on the hub. Further, the inter-ring spaces or annular cylinder grooves 18 have a depth below the bottom of the ring notches 19 at least equal to but preferably somewhat greater than that radial portion of a riser which lies outside the riser hub, that is, somewhat greater than the greatest radial dimension of a

riser so that the bearing of any riser of the cylinder will always be wholly a hub bearing. Said inter-ring spaces each have a width preferably slightly in excess of the thickness of the riser disk received and guided therein.

The pattern chain engages with said driving element or pattern cylinder substantially in the manner illustrated in Fig. 3, the hubs 10 of any risers upon a given bar having external bearing engagement in the aligned notches of the several rings during the travel of that bar around the cylinder, while each riser disk extends downwardly and is positively guided between two adjacent rings. To facilitate the entrance of the risers between the rings for guidance thereby I may round off or bevel the side edges of the ring disks, as indicated at 20, Fig. 3. The dimensions of 15 the rings and spaces between them are preferably such that the width of a space plus the width of a ring substantially equals the extent of one riser in the direction longitudinally of the cylinder, that is, the width of one control path. Since the risers have double hub bearings, one at each face of the riser disk, as 25 illustrated, each control path and each riser or sinker actually covers one inter-ring space and substantially one-half the ring at each 30 side of it.

In accordance with my invention, therefore, each riser, during the travel of its bar about the pattern cylinder, has external hub bearing support directly upon the cylinder, 35 and said hub bearing is a double one, afforded by the double hub portions of each riser seating in the respective notches of two adjacent rings. Said hub bearings going into the longitudinal cylinder grooves or aligned notches 40 definitely and positively position and support the risers. The pressure of each vibrator lever 1 at the time of contact of a riser with it is thus entirely removed from the bar on which that riser is positioned and is received directly by the cylinder through the 45 riser hub, externally of the latter. The bar or pin itself is completely "unloaded". This is of particular importance at the time mentioned, when the riser is engaging the vibrator lever 1 or other part to be moved, since a 50 positive and accurate actuation of the latter is assured, in contrast to the case where the chain bars have no support intermediate their ends or where there is no individual or external hub bearing support for the risers. 55 The same may also apply to the sinkers which may be similarly received and supported in the aligned ring notches while passing about the pattern cylinder. Further, the riser elements of each control line are additionally 60 positively and independently guided lengthwise of the chain during their passage about the cylinder, by the inter-ring spaces 18. With said construction and arrangement of 65 the risers and the provision of a pattern cylin-

der of the novel form described and with the resulting ability to use a cam or working face for the riser disk which is narrower than a "control path" or than the members to be moved, such as the vibrator levers 1, the possibility of a "harness-skip" is eradicated as far as the pattern mechanism is concerned, which latter has been the chief source of these expensive and wasteful defects in weaving. At the same time I obtain positive guidance 70 of the chain and accurate bearing support for its elements coupled with the benefits of said narrow operating or cam faces of the risers, and all with no sacrifice of flexibility and ease of assembling or alteration of the 75 chain as various patterns or weaves may require, since the pattern controlling elements, the risers and sinkers, of any single control path or "harness path" are individually and independently assemblable.

Other advantages in the disclosed pattern control mechanism in addition to those already pointed out will be apparent. It will be noted, for example, that with the described construction, including the arcuate links, the 80 connecting portions of the links lie outside the outer diameter of the pattern cylinder, that is, outside the circumference of the rings, while the bearings or eyes at the ends of the links have a diameter substantially the same as 85 that of the hubs of the risers or as that of the sinkers, and that two links together may have substantially the width of one riser or sinker or of a plurality of them. Accordingly I may insert extra links of this form intermediate 90 the ends of the bars in a comparatively wide chain, as illustrated for example at 12^a in Fig. 2, thus strengthening the chain and additionally insuring the maintenance of the bars in 95 parallelism. One or more of the links in such case will engage with the edge of a ring while 100 passing about the cylinder and afford additional bearing support for the chain upon the latter. Such provision of extra links intermediate the side edges of a chain is not possible 105 in a pattern mechanism of the usual form.

Any desired number of relatively narrow chains such as described may be employed in place of a single wide chain on a cylinder of given length in accordance with my invention, as illustrated in Fig. 4, and the several chains may themselves be of different lengths, 110 as shown in Fig. 5, with resultant possibility of great saving in chain stock and in the work of pattern building. Similarly in the box-motion chain, a plurality of narrower chains spaced sufficiently to accommodate the links and fasteners might be employed in place of a single wider one if for any reason such arrangement should be desired.

Also, because of the described construction of the risers, with double or oppositely projecting hub portions and central disk thereon, I may in some instances form the risers in units of two or more as shown for example, at 115 120 125 130

21 in Fig. 2. Such integral formation of a plurality of risers is not practicable in chains of the usual type, having wide cam faces, because of the difficulty in milling out the stock 5 between the individual riser cams while if said stock is not so removed the additional weight would be prohibitive of the use of a multiple-unit riser.

In any case, however, following my present 10 invention, I provide for independence of construction and assembly between each single control line of riser and sinker members in a chain, while at the same time obtaining positive guidance and positive external hub bearing support for said riser members in each 15 such line.

My invention is not limited to the particular embodiments thereof shown and described herein, its scope being set forth in the following 20 claims:—

1. In a pattern control mechanism for looms, in combination, a pattern chain having successive rows of risers held in selected relation in each row, said risers each including a disk-shaped body portion and a concentric hub portion projecting substantially equal distances at the two sides of said body portion, and a rotary chain-actuating element or pattern cylinder comprising a shaft having disposed along and coaxially with it a series of radial, transversely notched, spaced ring formations, the corresponding notches of all said ring formations for cooperation with a given pattern chain being 25 aligned lengthwise the shaft, each aligned series of notches to afford bearing means for the hubs of all risers of the particular row then cooperating with it, said ring formations being spaced and constructed to provide annular guide grooves for the side faces of the respective riser body portions of a depth sufficient to clear the inner faces of said riser body portions when their hubs have bearing in said 30 notches.

2. In a pattern control mechanism for looms, in combination, a pattern chain having successive rows of risers held in selected relation in each row, said risers each including a disk-shaped body portion and a central hub 35 portion projecting substantially equally at opposite faces thereof, a rotary chain-actuating element or pattern cylinder comprising a shaft having disposed along and coaxially with it a series of radial, transversely notched, ring formations circumferentially continuous between said notches, and spaced and constructed to provide guide means for the respective risers in the direction of their travel about the cylinder.

3. In a loom, pattern control mechanism 40 including a chain of transverse bars or pins, links pivotally connecting the latter, each bar carrying a row of plain or sinker members and cam or riser members arranged as called for by the pattern, corresponding members

on successive bars being in alignment lengthwise the chain to constitute one control line, each riser including a disk of a thickness substantially less than the width of a control line and a concentric cylindrical hub portion approximately equalling in length the width of one control line, the riser disk being substantially centrally disposed between the hub ends, and a chain-driving element or pattern cylinder comprising a series of coaxial, 70 equally spaced rings providing between them annular grooves each adapted to receive the riser disks of one control line of the chain, said rings having in their edges each a similar number of equi-angularly spaced notches 75 in alignment lengthwise the cylinder, for the reception and bearing support of the riser hubs externally thereof and at both sides of each individual riser.

4. In control chain mechanism for looms, 80 a rotary cylinder having a series of equally angularly spaced longitudinal groove formations interrupted by equally axially spaced annular groove formations, and a chain for cooperation therewith comprising successive 85 articulated rows of variously arranged risers held in selected arrangement, each riser including a disk received and guided in one of said annular groove formations and a concentric laterally projecting hub at each face 90 of said disk adapted to seat in said longitudinal groove formations and at such time positively to position and to furnish the entire bearing support of its riser, by external contact with the walls of the engaged groove 95 formation, said positioning and supporting action being substantially similar at both sides of each riser disk.

5. A pattern chain cylinder for looms, comprising an axial shaft portion and a series 100 of equally spaced ring or sprocket formations along the working length of the cylinder, providing between them circumferentially continuous spaces for the reception and guidance of disk-shaped risers, each ring or 105 sprocket having a plurality of equi-angularly spaced edge notches, with corresponding notches of successive rings in alignment lengthwise the cylinder throughout the width of any desired pattern chain, and each ring 110 being circumferentially substantially uninterrupted intermediate said notches, the latter providing bearings for elements of a pattern chain to be actuated thereby.

6. A pattern chain for looms, comprising 115 a series of transverse bars, means pivotally connecting said bars in substantial parallelism to form a chain, cam or riser units held in selected arrangement on said bars, aligned 120 units in the direction of the chain length constituting one control path or line, said riser units having each a centrally apertured hub portion and a cam or disk portion concentric therewith and substantially centrally 125 between its ends, said cam portion being of 130

a width markedly less than that of a control path or line, and said hub portion being constructed and proportioned to provide external hub bearing support at both faces of the 5 disk portion of its riser unit.

7. In a pattern chain mechanism for looms, an articulated pattern chain comprising successive rows of risers arranged and held as called for by the pattern, each riser including 10 a disk-shaped body portion and a hub portion projecting axially from said body portion at the opposite side faces thereof, sufficiently to afford means for external double hub bearing support of its riser.

15 8. In a pattern chain mechanism for looms, an articulated pattern chain comprising successive rows of risers arranged and held as called for by the pattern, each riser including a hub portion adapted to receive external 20 bearing support at both ends and a disk-shaped body portion thereon substantially centrally intermediate said hub ends.

9. In a pattern chain mechanism for looms, an articulated pattern chain comprising successive 25 rows of risers arranged and held as called for by the pattern, each riser including a disk-shaped body portion and a hub portion projecting axially from said body portion to substantially equal distances at the opposite side faces thereof and sufficiently to provide means for the external hub bearing support of its riser at both sides of the riser body portion.

10. In a pattern chain mechanism for 30 looms, a chain comprising a series of transverse bars carrying risers held in selected arrangement therealong, links at the opposite ends of the bars for hingedly connecting the successive bars, and means for securing said 40 links in position upon the bars including an annular groove near the ends of each bar and outside the outer links, and a fastener adapted to be received and retained in each groove and substantially completely surrounding the bar 45 axis to afford a side-thrust bearing for the link around substantially the entire circumference of the bar, said fastener formed of wire-like spring metal stock having its ends bent inwardly upon themselves but spaced 50 from each other providing an interrupted ring of a radial thickness double that of the stock at all points except that intermediate said opposed inturned ends.

11. In a loom pattern chain mechanism, a 55 chain composed of pivotally connected bars carrying individual and independently assemblable riser units located therealong in

selected relation, and a chain driving cylinder, said cylinder and each of said riser units being provided with cooperating formations 60 whereby each riser unit, during its travel about the cylinder will be restrained from movement in either direction lengthwise the cylinder.

12. In a loom, a pattern chain having risers 65 and locating means therefor, said risers including an operating or lever-engaging portion and a hub portion projecting at both sides thereof, and a chain-driving cylinder having spaced along it a plurality of concentric plates or rings, the construction and arrangement of said cylinder rings and risers being such that, during engagement of a riser with its particular vibrator-lever or the like to be actuated, the thrust or pressure of 75 said engaged member upon the operating portion of the riser is transmitted therefrom substantially equally by both sides or ends of the riser hub portion directly onto two adjacent cylinder plates or rings. 80

13. In a loom pattern chain mechanism, a chain composed of pivotally connected bars carrying individual and independently assemblable risers, means for locating the risers in selected position along the respective bars, 85 and a chain-driving cylinder, said cylinder and each of said risers being provided with cooperating formations whereby the cylinder, upon and during engagement with each riser, will directly engage and fix the latter in its 90 path of travel as to movement both axially and transversely of the cylinder.

14. In a loom, a cylinder for actuating a pattern chain, the latter having a plurality of chain lines of risers formed as structurally 95 independent units, said cylinder being constructed and arranged directly to engage and positively to position and restrain each riser during the travel of the latter about the cylinder as to movements both axially and transversely of the cylinder. 100

15. In a pattern chain mechanism for looms, an articulated pattern chain comprising successive rows of risers arranged and held as called for by the pattern, each riser including a disk-shaped body portion and a centrally apertured hub portion projecting axially from said body portion sufficiently to afford means for the external hub bearing support of its riser. 105 110

In testimony whereof, I have signed my name to this specification.

LEON H. BEYTES.
